UNITED STATES PATENT OFFICE.

LESTER S. KEILHOLTZ AND ERNEST DICKEY, OF DAYTON, OHIO, ASSIGNEES TO DELCO-LIGHT COMPANY, OF DAYTON, OHIO, A CORPORATION OF DELAWARE.

ENGINE.

Application filed August 3, 1923. Serial No. 655,503.

To all whom it may concern:

Be it known that we, LESTER S. KEILHOLTZ and ERNEST DICKEY, citizens of the United States of America, residing at Dayton, county of Montgomery, and State of Ohio, have invented certain new and useful Improvements in Engines, of which the following is a full, clear, and exact description.

10 The present invention relates to engines and particularly to engines of the type using poppet valves.

15 Among the objects of the present invention are reduction of noise, protection of the valve operating mechanism from dust and dirt, lubrication of the mechanism in a simple manner, and reduction of the transfer of heat from the hotter parts of the engine to the valve mechanism.

20 Other and further objects of the present invention will be apparent from following description, reference being had to the accompanying drawings wherein a preferred embodiment of one form of the present invention is clearly shown.

In the drawings:

Fig. 1 is a sectional view of an engine taken on line 1—1 of Fig. 2, showing the improved valve actuating mechanism; and

30 Fig. 2 is a sectional view taken on line 2—2 of Fig. 1.

Referring to the drawings, 20 is the cylinder of an internal-combustion engine connected with an intake pipe 21 and an exhaust pipe 22 leading to separate passages. The passage leading from the intake pipe 21 to the cylinder 20 is shown at 23 and is controlled by a valve 24 having a stem 25. The upper part of the cylinder is provided 35 with hole 26 leading from the passage 23 within which is press-fitted a valve guide 27 which extends beyond the top of the cylinder. This extending portion of the guide 27 functions as a guide for the valve spring 28 which is interposed between the top of the cylinder and a valve spring thrust seat 29.

40 The top of cylinder 20 carries a valve mechanism housing 30. Housing 30 is spaced from the cylinder by a gasket 31 for a purpose to be described, and is secured in place by bolts 32. The housing 30 includes side walls 34 and 35, a front

wall 36, a back wall 37, and a bottom wall 38. The side walls 34 and 35 are provided with aligned holes 40 for receiving a rocker arm pin 39. Pin 39 is hollow and the ends thereof are closed by plugs 41, so that the pin forms a reservoir for lubricant. The wall 34 is tapped to receive a hollow pin 43 having a reduced end 44 received by a suitable hole in pin 39 to lock said pin in position. The pin 43 provides a conduit through which the pin 39 is supplied with lubricant.

45 Valve actuating rocker arms 46 and 47 are rotatably and slidably mounted on the pin 39 and are separated from one another and held against the walls 34 and 35 respectively by a spring 48 which encircles the pin 39 and is interposed between the arms. The pin 39 is provided with tapped holes in the bottom thereof which receive felt plugs 49 through which the lubricant seeps and thence passes to the outer periphery 50 of the pin 39 to supply a limited amount of lubrication to the rocker arms 46 and 47.

50 Fig. 1 shows the valve gear for the intake valve and it is to be understood that the mechanism for operating the exhaust valve 55 is substantially the same.

The bottom wall 38 of the housing 30 provides a bearing 50 forming a guide for the portion 51 of the engine operated push rod 52. Portion 51 is engaged by an adjustable screw 54 which is carried by the rocker arm 47. When rod 52 and likewise portion 51 are moved upwardly and engage the screw 54 it will cause the rocker arm 47 to rotate about the pin 39 to move the valve 55 stem 25 and likewise cause the valve 24 to move from its seat. When the rod 52 moves downwardly the spring 28 will cause the valve to again seat.

55 The top edge of the side walls 34 and 35 slopes downwardly from the back wall 37 to the front wall 36 which extends to substantially the same elevation as the upper end of the valve stem 25 when in uppermost position. A cover 55 is provided for the housing 30 and is held in place by screws one of which is shown at 56. The cover 55 is formed to conform to the shape of the upper edge of the walls of housing 30, as shown in Fig. 1. The top wall of the cover 55 is provided with a hole 57 through which

the pin 43 extends so that lubricant can be placed in the pin 39 without removing the cover.

The invention is herein applied to an internal-combustion engine of the air-cooled type similar to the engine shown in the pending application of Keilholtz and Dickey Serial No. 390,247, filed June 19, 1920. The engine is provided with a draft tube 58 which encircles the cylinder 20 and the valve actuating mechanism. The tube 58 is provided with an opening 59 in the top thereof for the passage of air therethrough. This opening 59 is large enough to permit the withdrawal therethrough of the housing as a unit or the cover 55.

Certain advantages are apparent in the present invention, one of which is the removability of the housing and rocker arms as a unit. By merely removing the bolts 32, the housing and rocker arms can be removed as a unit without disturbing any of the adjustments. The rocker arm remains in position with respect to the housing and the 25 push rod guide slides from the push rod portion 51.

Only one place is necessary for oiling the rocker arms. The pin 39 upon which the arms are fulcrumed forms a reservoir in which an ample quantity of lubricant can be stored to provide lubrication for a long interval. Therefore frequent oiling is unnecessary. The rocker arms are not over lubricated. The felt plugs 49 distribute a limited amount of lubricant to the bearing surfaces of the rocker arm and pin. In this manner very little, if any, lubricant escapes from the housing into the path of air currents to collect the dirt circulating 40 with the air.

One member serves as a lubricant conduit to the reservoir and as a locating pin for the rocker arm fulcrum pin. This improved mechanism provides a device in which the reservoir is easily supplied with lubricant and in which the rocker arms are readily assembled or disassembled. After removing the pin 43, the fulcrum pin 39 can be withdrawn, permitting the rocker arms to be removed. The spring 48 provides means for maintaining both rocker arms in place upon the fulcrum when the mechanism is in its assembled position.

Ready access may be had for the adjustment of the actuating mechanism. Removal of the bolts 56 permits the withdrawal of the cover 55 through the opening 59 in the draft tube 58. After the cover is removed the adjusting screw can be actuated; and, by forming the housing with sloping walls, a gauge can be readily inserted through the opening 59 in the tube 58 and between the rocker arm and valve stem for testing the clearance between said members.

The improved mechanism provides quiet

engine operation, and the rocker arms and housing therefore are maintained relatively cool. The gasket 31 limits the conduction of heat from the hot cylinder to the rocker arms and housing. Gasket 31 also limits the transmission of noise producing vibrations from the engine to the housing. The noise producing vibrations which are transmitted to the housing and those that are produced in the housing are muffled by the housing.

While the form of mechanism herein shown and described constitutes a preferred embodiment of one form of invention, it is to be understood that other forms might be adopted and various changes and alterations made in the shape, size, and proportion of the elements therein without departing from the spirit and scope of the invention.

What is claimed is as follows:

1. In a device of the kind described, and in combination with an internal combustion engine cylinder, a housing supported by said cylinder above the upper end thereof; a hollow pin the ends of which are supported in bearings carried by said housing; a rocker arm located within said housing, and one end of which is adapted to engage and operate a valve of the engine; a push rod for operating said rocker arm; a removable cover for said housing, and which cover has a hole in its upper surface; and a hollow conduit the lower end of which engages said pin to thereby hold it in place within its bearings, and the upper end of which conduit extends through the hole aforesaid in the cover of said housing.

2. In a device of the kind described, the combination with a valve; of a valve gear comprising a rocker arm, a pin for said arm adapted to movably carry said arm, a support for said pin and means for holding the pin on the support, said means also forming a conduit for the passage of lubricant to said pin.

3. In a device of the kind described, the combination with a valve; of a valve gear comprising a rocker arm, a hollow pin adapted to form a lubricant reservoir and a fulcrum for said arm and having a passage leading to said arm, and means for holding the pin on the support, said means also forming a conduit for the passage of lubricant to said pin.

4. In a device of the kind described, the combination with a valve; of a valve gear comprising a rocker arm, a hollow pin adapted to form a lubricant reservoir and a fulcrum for said arm and having a passage leading to said arm, means for holding the pin on the support and which means also forms a conduit for the passage of lubricant to said pin, and means for restricting the flow of lubricant through said passage.

5. In a device of the kind described, the combination with a valve; of a valve gear comprising a rocker arm, a hollow pin adapted to form a lubricant reservoir and a fulcrum for said arm and having a passage leading to said arm, and means forming a conduit for the passage of lubricant to said pin, said means serving also to hold said hollow pin in proper position relative to said rocker arm. 10
In testimony whereof we hereto affix our signatures.

LESTER S. KEILHOLTZ.
ERNEST DICKEY.
